Philip A. Fenell

ATTORNEY.

UNITED STATES PATENT OFFICE

WILLIAM E. CULP, OF MONON, INDIANA

JAR AND CAP HOLDER

Application filed July 24, 1929. Serial No. 380,650.

The invention relates to jar, cap and can wrenches, and has for its object to provide a device of this character which may be utilized for rotating a jar cover, holding a jar during the cover removing operation or holding a can during a cutting operation.

A further object is to provide a holding device for jar covers, jars and cans comprising a U-shaped handle member formed from flexible material and provided with notched arms cooperating with enlargements carried by the ends of a contractile flexible member adapted to encircle an article and to grip said article upon compression of the handle member. Also to provide the ends of the flexible member with a plurality of enlargements adapted to engage the inner sides of the notched arms for adjusting the flexible member according to the circumference of the article to be gripped.

A further object is to form the flexible member enlargements by twisting the same into loops thereby reducing the cost of manufacture to a minimum and allowing the loops and the flexible member to be formed from a single strand of material.

A further object is to provide the opposite ends of the U-shaped handle member with arcuate arms curving to opposite sides of the contractile flexible member and terminating in upwardly offset eyes through which the opposite sides of the contractile member extend for supporting said contractile member. Also to anchor the inner ends of the flexible arcuate arms to the arms of the handle member by extending the same through apertures in said arms and bending the same around the arms of the handle.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:
Figure 1 is a perspective view of the holder.

Figure 2 is a top plan view of the device showing the same applied.

Figure 3 is a perspective view of one end of the contractile member.

Figure 4 is a vertical transverse sectional view through one of the arms of the handle member showing the supporting means for one of the supporting arms.

Referring to the drawing, the numeral 1 designates a cylindrical member adapted to be held or rotated and which member may be a jar top, a jar or a can, as the device is applicable for use in connection with any of these articles, and it is to be understood that the member shown is for purposes of illustration only.

The device comprises a U-shaped handle member 2 formed from flexible material and has its arms 3 provided with inwardly extending arms 4 having notches 5 for the reception of the ends 6 of the flexible contractile member 7, which is adapted to encircle the member 1 to be held or turned, and which contracting operation takes place when pressure is applied to opposite sides of the handle member 2. The ends 6 of the contractile member 7 are twisted to form loops 8 and 9, thereby forming spaced enlargements as clearly shown in Figure 2 to be placed to the inside of the arms 4 for initially contracting the contractile member 7 according to the circumference of the member 1 before the gripping operation. After the adjusting operation, the operator then grasps the handle member 2, squeezes the same, which action will contract the contractile member 7 into close binding engagement with the outer periphery of the member 1 for gripping and holding the same.

It will be noted that the only connection between the flexible member 7 and the handle is in the notches 5 and to maintain the contractile member 7 in normal position, arcuate supporting arms 10 are provided, which arms are formed from flexible material and provided with upwardly extending eyes 11, through which the opposite sides of the contractile member 7 extends, therefore it will be seen that the member 7 is supported and

the members 10 will contract with the member 7.

The outer ends of the arcuate flexible arms 10 are supported by the outer ends of the arms 3, and extend transversely through apertures 12 in the arms 3 and then are bent to form rectangular shaped loops 13 around the arms 3, therefore it will be seen that the loops 13 will positively hold the arcuate arms 10 in their relative relation.

From the above it will be seen that a wrenching device is provided which is simple in construction and constructed in a manner whereby all machine work is eliminated and the device can be twisted principally from flexible wire thereby reducing the cost of manufacture to a minimum and allowing the same to be constructed by unskilled labor.

The invention having been set forth what is claimed as new and useful is:—

1. A receptacle tool comprising a U-shaped handle member, a contractile flexible member, enlargements carried by the ends of the contractile flexible member, arms carried by the arms of the U-shaped handle member and having notches for receiving adjacent portions of the contractile flexible member in the path of the path of the enlargements and flexible arcuate arms carried by the arms of the handle member and supporting the contractile member at opposite sides thereof.

2. A receptacle tool comprising a U-shaped handle member formed from flexible material, the arms of said handle member terminating in inwardly extending notched arms, an annular contractile flexible member adjacent the ends of the notched arms, said contractile member having ends, integral enlargements carried by said ends, said ends being adapted to be received in the notches of the notched arms, flexible arcuate arms carried by the handle arms and terminating at opposite sides of the contractile member, upwardly extending arms carried by said last named arms and eyes carried by said upwardly extending arms and through which the opposite sides of the contractile member extends.

3. A receptacle tool comprising a U-shaped handle member, a contractile band carried by the handle member adjacent one end thereof and controlled by the handle member and arcuate arms formed from flexible material and supporting the contractile member at opposite sides thereof, said arcuate arms having their inner ends extending through apertures in arms of the handle member and looped around the arms of the handle member.

In testimony whereof he hereunto affixes his signature.

WILLIAM E. CULP.
